DISPLAY DEVICE

Lillian G. Englar, Crestwood, N. Y.

Application October 31, 1938, Serial No. 238,106

9 Claims. (Cl. 40—126)

This invention relates to display devices the character of which is illustrated in my co-pending application, Serial No. 47,268, filed October 29, 1935, which has matured into Patent No. 5 2,135,124 and is a continuation in part thereof.

The general purpose of such devices in avoiding the expense of displaying original articles is well understood, and it is a special aim here to present a novel manner of mounting dummy 10 cigars for making up representations of full boxes of cigars.

It is another purpose to make available a novel top display unit which may be incorporated in various forms of box representations.

15 Another object is to present a novel construction of display device which may be embodied in a very compact form, with a minimum of material and labor in production.

A further object is to evolve a novel box representation which may be utilized for various displays of different goods at will, thus reducing the bulk of materials required in stock, as well as lessening the cost materially for a large range of varieties.

25 It is an important aim to give a novel structure of individual article representation and in the mounting of individual article dummy mountings and box representation structure coordinated therewith.

30 Additional objects, advantages and features of invention reside in the construction, arrangement and combination of parts in the embodiment of the invention, as will appear from the following description and in the accompanying drawings, each or taken together, wherein

35 Figure 1 is a plan view of one form of blank for a box representation which may be utilized in a display utilizing my invention.

Figure 2 is a fragmentary longitudinal section 40 of a complete display utilizing the structure of Figure 1.

Figure 3 is a cross section of the structure of Figure 2.

45 Figure 4 is a fragmentary top view of the display of Figure 2.

Figure 5 is a view similar to Figure 3, showing a modification.

50 Figure 6 is a longitudinal sectional view of a further modification of the invention adapted to mounting on various boxes, or box forms.

Figure 7 is a fragmentary top view showing one end of the display of Figure 6.

55 Figure 8 is a fragmentary cross section showing a modified lid representation for use with the structure of Figure 6, and others.

Figure 9 is a perspective view of a modified box representation.

Figure 10 is a fragmentary section of one end of a top display unit suitable for use with the structure of Figure 9.

Figure 11 is a detail of the blank for the form of Figure 9.

Figure 12 is a fragmentary front elevation of the device of Figure 9.

There is illustrated in Figures 1 to 4, details 10 of a dummy box and content disclosed in my said prior application. This consists of a one-piece pulp board blank 10 from which a complete box, lid, and raised bottom or tray may be formed. It includes a single plate constituting a combined tray 11 and integral lid-base extension 12 of rectangular form, the tray having an area and form corresponding to that of a conventional cigar box, and the lid extension being of approximately the same shape and size, 20

being continued integrally from the rear edge of the tray. An ear 13 is cut in the tray 11 folded downwardly and rearwardly on a line coinciding with the rear edge of the tray 11. At each end of the tray, end or side wall-legs 14 are integrally attached, foldable downwardly, and having front and back wall extensions 15 and 16 thereon foldable beneath the tray to lie respectively in line with the front and rear edges of the tray.

Between these extensions, parallel to the tray 30 ends, outer end-wall plates 17 are integrally formed on the wall legs, foldable upwardly to lie against the legs 14 and to project slightly above the tray, as indicated. The ear 13 is secured to the extensions 16.

35 A front wall plate 18 is formed integrally on the front edge of the tray 11, foldable downwardly to lie outwardly of the inturned front wall extensions 15 of the legs 14, to which it is secured.

40 From the outer longitudinal edge of the front wall plate 18, a bottom plate 19 is extended having a transverse rear wall plate 20 formed integrally thereon turned upwardly against the outer sides of the rear wall extensions 16 and 45 secured thereto, giving body to this rear wall and forming a continuous outer surface thereon.

Within the plate 19 an easel leg 21 is cut, with a brace 22 engageable in a slot 24 in the plate to hold the leg 21 in proper position to support 50 the device leaning backwardly as desired.

Upon the plate 11, there are secured a multiplicity of closely parallel, individual cigar dummy units 25, each consisting of a pulp stamping 26 embossed to represent in relief the upper side 55

portion and ends of a cigar, and an enclosure of transparent Cellophane tubing, or the like. The embossing is quite thin, and U-shaped in cross section, as well as longitudinally, formed with 5 surface relief representation of leaf edges and ribs, and of a texture and color to closely resemble tobacco. Each embossing is enclosed in a portion of transparent sheet tubing 27, such as Cellophane, cellulose acetate or other suitable 10 transparent material of which there are stock tube forms on the market available for the use contemplated. The tube portions project a substantial distance beyond each end of the embossing, and are not folded in or cemented to 15 close the ends of the tubes, but are left longitudinally projecting and open and secured by staples 28 to the tray 11 at the front ends of the tubes, and to the lid base 12 near the line at which the outer face of the rear wall plate 20 20 lies when folded up against the extensions 16. The front ends of the tubes are trimmed flush with the front edge of the tray but the rear ends may be left at random lengths to be concealed by a top lid and label, as will be described. Upon 25 the front ends of the tubes a strip of pulp stock 29 is laid and secured by staples to the tray, being of a height and width to represent the front edge of a cigar box when covered with suitable gummed ornamented tape 34 such as is actually used on 30 the edges of cigar boxes in the trade.

A lid top plate 30 is secured on the lid base extension 12 in alinement with its outer edges, and projecting over the tray slightly so that its 35 rectangular inner edge will represent the inner side of a back wall of a conventional cigar box. Upon this plate 30 there is secured a label 31 the outer edges of which may be at or near the corresponding edges of the lid plate, but the inner edge preferably projects slightly beyond the edge 40 of the plate so as to conceal the same and thereby making it unnecessary to paste white paper on that part or otherwise coat or cover it.

The extension 12, the plate 30, and the label, thus serve not only to represent the lid but also 45 the connected part of the rear wall of a box of conventional form, and with the dummies 26 secured in place as shown, after the outer faces of the sides and ends of the parts 17, 18 and 20, are suitably covered, and the usual ornamental 50 tape 34 applied to the various edges at 29, and 17 and around the lid extension 12, plate 30 and label 31, the appearance of a conventional cigar box filled with cigars is created.

If desired, the extension 12 may be omitted as 55 shown in Figure 5, a back wall 32 being extended downwardly from the rear edge of the tray 11, which may be formed as before described, except that the ear 13 is not stamped therefrom. The portions 19 and 29 may also be omitted, as is also 60 shown in Figure 5, the front and rear wall extensions 15 and 16 being formed as before, the latter being secured to the wall 32. The rear ends of the tubes 27 are stapled to the tray and trimmed flush, a built-up rear wall edge representation 23 similar to the one 29, being secured 65 upon the rear edge portion of the tray 11 over the ends of the tubes and flush with the rear wall 32, and this edge 23 may have a lid plate rigid or actually hinged thereon so that it may 70 be folded over the dummy units, and thereby protect them from dust when not in use, as well as making it possible to adapt this display to smaller space. When made rigid the appearance 75 will be the same as in the article of Figure 3, when viewed from above. The bottom being

open, smaller items of display may be held within the article, and it is at the same time lighter, and cheaper.

In Figures 6 and 7 a further utilization of the invention is indicated, which consists solely of 5 a tray plate 40 to which units 28-27 similar to those already described are secured. The tray is formed with downturned flanges 41 at front and rear to which the ends of the tubes 27 may be 10 stapled, as at 42, so that the staples will not show above. At each end the tray is provided with hook-like hangers 43 which may be of metal, arranged so that they can be engaged over the top edges of the end walls of a box or box representation of any standard size and support the tray 15 within the box at the desired level. Displays of dummies representing respectively various brands may thus be made up and mounted alternatively in the same box or box representation at will, enabling change of displays quickly and with a 20 minimum disturbance of material.

The tray insert may also be made without the hangers, as in Figures 8 and 11, and mounted in a box element 44, such as shown in Figures 9, 25 11, and 12. In this instance a complete box body 45 may be made up, into which various tray units 46 may be slidably engaged, so that when so engaged the appearance of a full box of cigars with or without lid may be effected, the lid being either on the box or on the tray—either rigidly 30 attached as in Figure 3, or hinged as in Figure 8, or it may be omitted. In this case the tray 46 is formed as a simple flat plate to the front and rear edge portions of which the ends of the tubes 27 are stapled, and trimmed flush with the adjacent respective front and rear edges, and built-up wall edge representations 41 are stapled to the plate over the tube ends at front and rear edges of the tray 46.

The blank for a box form to receive this tray 40 is shown in Figures 9, 11 and 12, and consists of a bottom proper 48, of rectangular form, defined by scored lines 49 if desired, to facilitate folding. It corresponds in size and shape to the plan of the box to be simulated. A front wall 50 is 45 integrally extended from the front edge of this bottom 48, and being of slightly greater length than the bottom as defined by the scored lines, so as to allow for the thickness of material folded up at the ends of the bottom to form the inner 50 end walls 51. The latter are integrally formed at the ends of the bottom. These walls have tabs 52 formed at their front edges, which are folded inward and secured against the inner face of the front wall 50 by staples or otherwise. The 55 walls 50 and 51 are of the same height when the box is formed, and are of a height materially less than that of the full height of the corresponding 60 walls of the box to be represented when the article is completed. A back wall 53 is formed integrally on the rear edge of the bottom 48 of a height slightly greater than that of the parts 50 and 51, and of a length corresponding to or slightly less than that of the front wall 50. 65 From its ends integral outer end wall extensions 54 are continued, the bottoms of which abut the rear ends of the inner end walls 51 in the blank, and the bottom edges 35 of the wall 54 are slightly below the scored line of the rear edge of the bottom 49, so that when the walls 51 and 53 70 have been turned upward at right angles to the bottom, the walls 54 may be folded horizontally toward the front against the walls 51, and will lie with their bottom edges flush with the lower face 75

of the bottom 48. After such folding the walls 54 are secured to the walls 51.

The upper edges of the outer end walls are defined by score lines 55, at a height considerably above the top edge of the back wall 53, for reasons which will appear, and above this score line there is an integral extension 56, foldable inwardly and downwardly to lie with its outer rectilinear edge parallel to the top edge of the inner wall 51 in the formed box representation, forming a horizontal groove 57 in the inner side of each end of the box representation. The groove is adapted to receive freely and slidably the end edges of the plate 46 with the assembled display thereon, consisting of the units 26—27 secured as before described.

The upper edges of the outer end walls are defined by score lines 55, at a height considerably above the top edge of the back wall 53, for reasons which will appear, and above this score line there is an integral extension 56, foldable inwardly and downwardly to lie with its outer rectilinear edge parallel to the top edge of the inner wall 51 in the formed box representation, forming a horizontal groove 57 in the inner side of each end of the box representation. The groove is adapted to receive freely and slidably the end edges of the plate 46 with the assembled display thereon, consisting of the units 26—27 secured as before described.

It will be seen that in the use of the invention, the display is made up essentially by stapling the desired unit cigar representations to a tray or plate or board element to represent the content 35 of a container, this being coordinated in the various ways described, with a box representation, or the tray itself made in such form that it integrally represents the box as well as contents.

It will also appear that the invention makes possible the close simulation of individual cigars by the method used, using the individual tubes around the individual embossments of the cigars and that it enables the attachment of the units to form a complete display without expensive or complicated structural features or manipulations, but employing the simple operation of attachment by staples such as are used in offices and elsewhere to secure papers together, or to attach various articles together. In these the edges 50 of the trays or other parts may be inserted under the stapling head and the machine operated in the familiar ways well known to force the staple ends through the parts and clinch them.

The use of the built-up wall portions 29 or 41, or the overlying lid section 30—31 or the down-turned tray flanges 41 accomplish concealment of the stapled parts and enable effective simulation of box parts at the same time.

I claim:

1. In a display article, a tray plate, a plurality of display article units having respective transparent enclosures projecting beyond the article units at opposite sides, fastening means engaged through the projecting portions of the transparent enclosures and the tray plate, and means simulating parts of box elements superposed in abutment over the fastened portions of the transparent enclosures.

2. In a display article for simulating packages of cigars, a tray plate element, a plurality of individual cigar simulating members, respective tubular transparent flexible sheet material enclosures having the individual cigar simulating

members slidably engaged therein, the ends of the enclosures projecting beyond the respective enclosed cigar simulating members, staples engaged through the projecting portions of the enclosures and the tray in securing relation, and 5 container-simulating parts connected to the tray in a relation to the tray and cigar simulating members to form in appearance a complete container and contents, certain of the container-simulating parts being positioned over the projecting end portions of said enclosures.

3. The structure of claim 2 in which the tray plate has an integral extension in the same plane in a form and area corresponding to those of a lid of a container represented, said enclosures being projected over the extension and secured thereon, and a label bearing member corresponding to the area of a lid for the represented container, secured upon said extension and lying over the projected portions of the enclosures of a 20 thickness to support the label a material distance above the enclosures to simulate the edge of a box as one of the said parts simulating container parts.

4. The structure of claim 2 in which one of said 25 container-simulating parts secured over the projecting portions of the enclosures has a lid projected therefrom.

5. The structure of claim 1 in which a box element is provided having a form and size to 30 receive the tray therein at the upper part of the box element, said box element having a low front wall portion and grooves in the inner sides of the side walls to receive the tray slidably.

6. The structure of claim 1 in which a box element is provided having a form and size to receive the tray therein at the upper part of the box element, said box element having a low front wall portion and grooves in the inner sides of the side walls to receive the tray slidably, and 40 having a rear wall portion higher than the groove.

7. A box element of the character described consisting of a blank having a rectangular bottom formed with integral front, rear and side wall extensions adapted to be folded upwardly 45 to form respective sides of a box, the front wall being of a height not exceeding that of said side walls, said rear wall having integral outer side wall extensions at each end adapted to be folded forwardly when the back wall is erected and being of a height much greater than that of the said side walls, and respective upper parts said last named extensions folded inwardly and downwardly with their outer edges in spaced relation to the top edges of the side walls, to form grooves 50 to receive a plate element slidably therein.

8. The structure of claim 8, including a tray plate slidable in the grooves having a display of articles secured thereon and at least a front upstanding wall top edge portion coordinated with the upper edge portions of the outer side walls to form the appearance of the upper portion of a filled standard container.

9. The structure of claim 8 including a tray plate slidable in the grooves and having a goods display secured thereon and having at its front edge an upstanding wall top edge element arranged and constructed to extend between the upper edge portions of the outer side walls and a portion at its rear edge of similar effect and 65 having a lid projected from the rear outer side thereof.

LILLIAN G. ENGLAR.
